Filed Dec. 10, 1971, Ser. No. 206,975

Term of patent 14 years

Int. Cl. D24—02

U.S. Cl. D83—1 U

Fig. 1

Fig. 2

FIG. 1 is a perspective view of a biopsy tray showing my new design, and

FIG. 2 is a side elevational view thereof.

The bottom of the biopsy tray is substantially plain with two ribs which coincide with the top grooves extending therefrom, and the opposite side of the biopsy tray is a mirror image of that side shown in FIG. 2.

I claim:

The ornamental design for a biopsy tray, substantially as shown and described.
